UNITED STATES PATENT OFFICE.

CHARLES G. MARKS, OF WAUKEGAN, ILLINOIS.

STOOL AND THE LIKE.

Application filed January 17, 1925. Serial No. 3,025.

To all whom it may concern:

Be it known that I, CHARLES G. MARKS, a citizen of the United States, and a resident of Waukegan, in the county of Lake and 5 State of Illinois, have invented a certain new and useful Improvement in a Stool and the like, of which the following is a full, clear, and exact description, such as will enable others skilled in the art to make and use 10 the same.

My present invention relates to stools and the like for seating customers at the counters of cafés, restaurants, and similar places, and has more particular reference to the manner 15 of constructing and assembling the divers parts to the stool.

One of the objects of my invention resides in providing a stool having a standard that is fabricated from sheet metal so that its 20 weight is materially reduced, and said standard is so constructed at its upper and lower ends that it will readily receive and hold respectively the bushing for the spindle of the rotatable seat and the widened or flared base 25 for supporting the standard. Also I have provided a bracket that is secured to the under-side of the seat, which bracket is formed from a pattern cut out of sheet metal that is bent so as to provide an integral 30 spindle for assembly with the bushing in the upper end of the standard and has arms coacting with the seat. The whole device is novel and sturdy in construction, is capable of ready assembly, and is made 35 from a few parts by simple assembly operations so that it may be manufactured at an economical figure and the stool sold for a moderate price. Further objects will be apparent after an understanding of my invention 40 is had,

I prefer to carry out my invention and accomplish the aforesaid objects in substantially the manner hereinafter fully described and as more particularly pointed out 45 in the claims, reference being now made to the accompanying drawings that form a part of this specification:

Fig. 1 is a vertical section taken longitudinally through the standard of the stool.

Fig. 2 is a transverse section on line 2—2 of Fig. 1, and drawn to an enlarged scale.

Fig. 3 is a similar view on line 3—3 of Fig. 1.

Fig. 4 is a side elevation of the seat bracket, a portion thereof being in section.

Figure 5 is a plan of the blank from which the bracket is fabricated.

Fig. 6 is a perspective of the bracket and spindle after the blank has been formed.

Fig. 7 is a perspective of the bearing disk 60 removed from the bracket.

The accompanying drawings illustrate a typical or preferred embodiment of my invention and in the drawings similar reference characters designate like parts 65 throughout the several views.

Referring primarily to Figs. 1, 2, and 3 it will be observed the standard 10 preferably is formed from sheet metal of a desirable gauge for sturdiness and is hollow or cylindrical from end to end and it is given a slight taper from the bottom towards the top. The standard may be rectangular, circular or other desired shape in cross-section, and the longitudinal edges of the pattern 70 are secured together after the cylinder has been formed by a seam 11 that is disposed upon the interior of the standard so that the exterior surface of the wall formed by the adjacent portions of the sheet metal will be 75 flush and substantially smooth. The base 12 is preferably a metal stamping of any suitable design and in its upper portion is provided with a shoulder or shelf 13 from which extends an upwardly projecting stub 80 14. This stub is of a sectional contour the same as the standard 10 and it tapers inwardly towards its upper end, and one of its walls has a slot or recess 15 cut downwardly from the upper edge so that the 85 metal will extend upon each side of the seam 11 of the standard. In assembling the fitting is accomplished by forcing the one element upon the other and securing the same in position by spot-welding or the like. 90

A metal bushing 16 of slightly greater diameter than the diameter of the upper end of the standard is driven into the latter until the lateral flange 17 on the upper end of the bushing comes into contact with the 100 edge of the metal forming the standard. This driving action or fitting of the bushing into the standard will bulge the side walls of the latter outwardly as indicated at 17 in Fig. 2 of the drawing and the parts 105 are then spot-welded together to prevent accidental dislodgement.

In order to mount the seat 19 of the stool on the standard and permit the same to be rotated thereon, I have provided a bracket 110

upon the underside of the seat that consists of a spider having preferably three horizontal arms 20 that project laterally and radially from the upper end of an integral 5 spindle 21. The bracket is preferably formed from sheet metal of a heavier gauge than that of the standard and is formed from a blank of substantially rectangular shape as illustrated in Fig. 6 of the drawings. There are two longitudinal slots 22 cut out into the blank from one edge thereof so that the fingers 20 may be formed by bending the metal outwards. The opposite portion of the blank is preferably rolled 10 into a cylindrical shape so that the opposite edges of the metal are brought together and may be butt-welded to secure the same together. After the bracket has been shaped and assembled in the manner described a 15 washer or apertured disk 23 is slipped onto the spindle 21 up to the juncture of the latter with the arms of the spider and the washer assembled therewith by welding or otherwise, so that it assists in maintaining 20 the cylindric formation of the spindle in the event the edges of the metal should accidentally become separated. This washer 23 also provides a bearing element to engage 25 with the upper surface of the flange of the bushing 16 when the spindle is inserted into the latter. The seat 19 is assembled with the bracket by means of screws or the like 30 that are passed through screw-holes 24 in

the outer ends of the arms of the bracket and are screwed into the under-side of the 35 seat, which is usually of wood or is provided with means to receive the screws.

While I have herein illustrated and described a specific manner of carrying out my invention it will be obvious to others 40 that divers changes and modifications may be made without materially departing from the principles involved, and I therefore desire it understood that such changes as may be made are fully contemplated as coming 45 within the scope of the appended claim, and I desire such breadth of interpretation given to said claim as is warranted by the prior state of the art.

What I claim is:—

A stool comprising a standard formed from sheet metal and cylindrical in cross-section, a bushing driven into the upper end of said standard whereby to bulge the 55 walls of the latter outwardly, a base having a tapered extension inserted in the lower end of said standard, a rotatable seat, a spindle consisting of a cylinder of sheet metal removably mounted in said bushing, 60 and integral sheet-metal arms projecting radially from the upper end of said spindle and secured to the underside of said seat.

Signed at Chicago, Cook County, Illinois, this 12th day of January, 1925.

CHARLES G. MARKS.
